UNITED STATES PATENT OFFICE.

ANTHONY ARCADU, OF PEEKSKILL, NEW YORK.

CHEST LOCK.

Application filed December 6, 1927. Serial No. 238,185.

This invention relates to chests and other like containers and has special reference to a locking device for chests.

One important object of the invention is to improve the general construction of devices of this character.

A second important object of the invention is to provide an improved form of secret or hidden lock for chests having hinged lids, the lock being operated without a key by means of a secreted button.

A third important object of the invention is to provide an improved form of lock for chests having hinged lids wherein the hinges themselves will, when the lid is in fully closed position, form the main locking means, the leaves of the hinges being secured against swinging movement upon the lid being placed in its fully closed position.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a plan view of the chest with the improved lock, the lid being shown in fully opened position.

Figure 2 is a side elevation, partly in section and partly broken away, of one of the hinges in its fully opened position.

Figure 3 is a view similar to Figure 2 but showing the hinge closed and ready for movement to locking position.

Figure 4 is a view similar to Figure 3 but showing the hinge in locking position.

Figure 5 is a longitudinal vertical section through the lid and housing thereon.

Figure 6 is a vertical transverse section through the lid and housing.

Figure 7 is an enlarged section on the line 7-7 of Figure 1 with the lid closed.

Figure 8 is a section on the line 8-8 of Figure 7.

Figure 9 is an enlarged detail section on the line 9-9 of Figure 1 with the lid closed.

In the embodiment of the invention herein illustrated there is disclosed a chest having the usual side walls 10, rear wall 11, front wall 12, and cover 13. Extending along the top of each side wall 10 is a plate 14 which is preferably seated in a suitable channel

cut into the top of the wall 10 so that the upper surface of the plate 14 is flush with the top of said wall. This plate is secured in position by suitable screws and adjacent the front end of the plate is a key hole slot 15 arranged with the larger or entry end of the key hole toward the rear. Also the plate 14 has a centrally disposed pin hole 16.

The lid is connected to the body of the chest by a pair of hinges each of which has a shorter leaf 17 and a longer leaf 18. The shorter leaf of each hinge is slidably mounted on the rear portion of a respective plate 14, the mounting being effected in the following manner. In the leaf 17 is formed a pair of longitudinal slots 19 of T-shape in cross section and in each slot is fitted a T-shaped guide block 20 secured to the plate 14 by screws 21. Thus the leaf 17 has limited

sliding movement on the plate 14. The long leaf 18 is screwed firmly to the underside of the lid 13. Near the free end of each long leaf is fixed a headed pin 22, the pin being positioned at such point that, with the hinges slid as far back as they will go and the leaves folded together (see Figure 3), the pin will pass through the large end of the key hole slot. The head on this pin is of greater diameter than the width of the smaller end of said slot so that, with the hinge slid forward, as in Figure 4, the leaves cannot be unfolded and the lid cannot be raised. Preferably the hinge is countersunk into the lid as shown in Figures 7 and 8 but I may, if I so desire, omit the countersinking as shown in Figure 5.

In order to secure the lid in its forward position the upper leaf is provided with a pin hole 23 which, with the hinge in forward position, registers with the pin hole 16, and through the hole 23 slides a pin 24 which projects upwardly through the lid 13 and has its upper end connected to the outer end of a lever 25 pivoted to the lid through a fulcrum block or bearing 26. A spring 27, beneath the inner end of this lever, urges the pin into protracted position so that, while the pin may retract to permit closing of the leaves as in Figure 3, as soon as the pin alines with the pin hole 16 it will be forced into that hole and the hinge cannot be slid on the plate 14 until the pin is again withdrawn.

On top of the lid 13 is an ornamental housing 28 across which runs a shelf 29 and this housing covers the levers and pins and conceals them both from being tampered with and from view. Connecting the inner ends of

the levers is a presser bar 30 the central portion of which extends over the shelf 29 and is supported thereabove by springs 31. Projecting from the center of this bar through the 5 top of the housing is a presser button 32 which has its upper end carved to form part of and be concealed by the ornament 33. By this means a person, knowing the secret of the lock, can open the chest by pushing down on 10 the button 32, which frees the pins from the holes 16, and then sliding the lid back to allow the pins 22 to pass out of the large end of the slots 15 as the front of the lid is raised.

In order to aid in keeping the back of the 15 lid from being sprung up there is mounted on the wall 11 a pair of eye plates 34 and in recesses 35 in the underside of the top pin members 36 which, when the lid is closed, as in Figure 9, will engage in said eye plates 20 upon the lid being slid forwardly, the lid in said figure being shown as closed but not slid forwardly to its final position for closing the chest.

There has thus been provided a simple and 25 efficient device of the kind described and for the purpose specified.

It is obvious that minor changes may be made in the form and construction of the invention without departing from the material 30 spirit thereof. It is not, therefore, desired to confine the invention to the exact form herein shown and described, but it is desired to include all such as properly come within the scope claimed.

Having thus described the invention, what 35 is claimed as new, is:

1. In a device of the kind described, a plate having a key hole slot at one end, a hinge having a short leaf slidably mounted on said 40 plate and a long leaf foldable to bring its free end over the key hole slot, and a headed pin carried by said long leaf and engageable in said key hole slot to enter the wide end and slide into the narrow end.

2. In a device of the kind described, a plate having a key hole slot at one end, a hinge having a short leaf slidably mounted on said plate and a long leaf foldable to bring its 45 free end over the key hole slot, a headed pin carried by said long leaf and engageable in said key hole slot to enter the wide end and slide into the narrow end, and means to secure the hinge against sliding movement on the plate.

3. In a device of the kind described, a plate having a key hole slot at one end, a hinge having a short leaf slidably mounted on said plate and a long leaf foldable to bring its 50 free end over the key hole slot, a headed pin carried by said long leaf and engageable in said key hole slot to enter the wide end and slide into the narrow end, said plate also having a pin hole opening therein, and a spring pressed retractile pin carried 55 by said long leaf and positioned to enter said

pin hole upon the headed pin being moved into the narrow end of the key hole slot.

4. In combination, a chest having front, rear and end walls, a lid for said chest, a pair of plates mounted on the top of said end walls and each having a key hole slot adjacent its front end, a pair of hinges each having a short leaf slidably mounted on a respective plate at the rear end thereof, said hinges each having a long leaf secured to the underside of said lid, and a headed pin adjacent the free end of each long leaf and adapted to enter the wide end of the respective key hole slot and move into the narrow end by sliding of the hinge on the plate. 80

5. In combination, a chest having front, rear and end walls, a lid for said chest, a pair of plates mounted on the top of said end walls and each having a key hole slot adjacent its front end, a pair of hinges each having a short leaf slidably mounted on a respective plate at the rear end thereof, said hinges each having a long leaf secured to the underside of said lid, a headed pin adjacent the free end of each long leaf and adapted to enter the wide end of the respective key hole slot and move into the narrow end by sliding of the hinge on the plate, and means to secure the hinges against sliding movement on the plates. 95

6. In combination, a chest having front, rear and end walls, a lid for said chest, a pair of plates mounted on the top of said end walls and each having a key hole slot adjacent its front end, a pair of hinges each having a short leaf slidably mounted on a respective plate at the rear end thereof, said hinges each having a long leaf secured to the underside of said lid, a headed pin adjacent the free end of each long leaf and adapted to enter the wide end of the respective key hole slot and move into the narrow end by sliding of the hinge on the plate, said plates each also having a pin hole opening therein, and spring pressed retractile pins carried by said long leaves and positioned to enter said pin holes upon the headed pins being moved into the narrow ends of the key hole slots. 100

7. In combination, a chest having front, rear and end walls, a lid for said chest, a pair of plates mounted on the top of said end walls and each having a key hole slot adjacent its front end, a pair of hinges each having a short leaf slidably mounted on a respective plate at the rear end thereof, said hinges each having a long leaf secured to the underside of said lid, a headed pin adjacent the free end of each long leaf and adapted to enter the wide end of the respective key hole slot and move into the narrow end by sliding of the hinge on the plate, said plates each also having a pin hole opening therein, spring pressed retractile pins carried by said long leaves and positioned to enter said pin holes upon the headed pins 110

115

being moved into the narrow ends of the key hole slots, and means for simultaneously retracting said retractile pins.

8. In combination, a chest having front, rear and end walls, a lid for said chest, a pair of plates mounted on the top of said end walls and each having a key hole slot adjacent its front end, a pair of hinges each having a short leaf slidably mounted on a respective plate at the rear end thereof, said hinges each having a long leaf secured to the underside of said lid, a headed pin adjacent the free end of each long leaf and adapted to enter the wide end of the respec-

tive key hole slot and move into the narrow end by sliding of the hinge on the plate, said plates each also having a pin hole opening therein, spring pressed retractile pins carried by said long leaves and positioned to enter said pin holes upon the headed pins being moved into the narrow ends of the key hole slots, means for simultaneously retracting said retractile pins, a housing on said lid concealing said means, and a concealed button exterior of said housing for operating said means.

In testimony whereof I affix my signature.

ANTHONY ARCADU.
